Melvin L. Kramer, Hoboken, N. J.

Application July 29, 1944, Serial No. 114,625

Term of patent 14 years

(Cl. D42—8)

To all whom it may concern:

Be it known that I, Melvin L. Kramer, a citizen of the United States, residing at Hoboken, in the county of Hudson and State of New Jersey, have invented a new, original, and ornamental Design for a Combined Watchcase and Strap Therefor, of which the following is a specification, reference being had to the accompanying drawing, forming part thereof.

Figure 1 is a plan view of a combined watchcase and strap therefor showing my new design, and

I claim:

The ornamental design for a combined watchcase and strap therefor, as shown.

MELVIN L. KRAMER.
